[57] **CLAIM**

The ornamental design for a sprinkler head splash guard, as shown and described.

DESCRIPTION

FIG. 1 is a top front perspective view of a sprinkler head splash guard showing my new design;

FIG. 2 is a side elevational view thereof, the opposite side being a mirror image;

FIG. 3 is a bottom plan view thereof;

FIG. 4 is a top plan view thereof;

FIG. 5 is a front elevational view thereof;

FIG. 6 is a rear elevational view thereof;

FIG. 7 is a top perspective view of a second embodiment thereof;

FIG. 8 is a side elevational view thereof, the opposite side being a mirror image;

FIG. 9 is a bottom plan view thereof;

FIG. 10 is a top plan view thereof;

FIG. 11 is a front elevational view thereof; and

FIG. 12 is a rear elevational view thereof.

FIG. 7

FIG. 9

FIG. 10

FIG. 8

FIG. 11

FIG. 12
